United States Patent Office.

SAMUEL F. COVINGTON, OF CINCINNATI, OHIO.

Letters Patent No. 77,593, dated May 5, 1868.

IMPROVEMENT IN REGISTERS FOR RAILROAD-FARES.

The Schedule referred to in these Letters Patent and making part of the same.

TO ALL WHOM IT MAY CONCERN:

Be it known that I, SAMUEL F. COVINGTON, of Cincinnati, in the county of Hamilton, and State of Ohio, have invented a new and useful Improvement in Devices for Registering Railroad-Fares; and I do hereby declare that the following is a full, clear, and exact description of the same, reference being had to the annexed drawings, making part of this specification, in which—

Figure 1 is a perspective view of the arm of a car-seat with the register attached.

Figure 2 is a side elevation of the register.

Figure 3 is a vertical longitudinal section.

Figure 4 is a key; and

Figure 5 is a perspective view of one of the boxes.

The same letters employed in all the figures indicate the same parts.

A is the arm of the car-seat. In the top of the arm is a recess or two recesses, where there is no arm in the middle of the seat. I have shown the ordinary construction, with a single arm at the aisle-end of the seat. The location of the recess may be varied according to circumstances. B is a metallic box, with a glass top-plate set a little above the sides of the box, leaving a narrow opening, through which the check-plates may be introduced. There are pins, B' B', projecting from the ends of the box to hold the boxes in the recess, where they are secured by a hinged lock-plate, C, (the key of which is carried by the conductor,) the plate shutting down on the pins on one end of the boxes. Within the box is a false bottom, pressed upwards by the spring E. F is the glass top-plate, and G a pin, which, projecting from the false bottom, is pressed against the bottom of the glass plate by the spring. The point of the pin may be bevelled on the side towards the opening under the glass plate. The box being separated, by a longitudinal partition, into two similar compartments, the parts D, E, and G are introduced into each compartment. The checks, H, are thin metallic plates, having the names of the stations on the road engraved thereon. A sufficient number of these must be furnished the conductor. The top of the false bottom has engraved on it the word "vacant." The bottom of the box is hinged thereto, and is secured by a lock, I, of which the key, K, is kept at the office at the end of the route.

When the car is starting on its trip, all the boxes will show the word "vacant." When a passenger pays his fare or delivers a ticket, to the conductor, the latter will insert the checks, H, through the opening under the glass plate. The checks, having a hole through them, will be caught by the pin G, so that it cannot be withdrawn. Two checks must be used in each case—one to indicate the place from which, the other the place to which the passenger has paid his fare. The checks will thus always indicate what seats are vacant, either in not having been occupied at all, or showing the names of stations that have been passed. The passenger will be protected by notice that a seat, though temporarily vacant, belongs to some one, and he may claim it on his return to it.

When the car reaches the end of the route, some one connected with the office unlocks the boxes and makes up an account of fares, with which that returned by the conductor must correspond. The conductor may change the boxes when a passenger desires to change his seat. This is done by unlocking the upper lock-plate.

What I claim as my invention, and desire to secure by Letters Patent, is—

1. In combination with the seat of a railroad-car, a box, so constructed that it may receive check-plates, showing the names of the station to and from which the passenger has paid his fare, and so arranged that the plates can only be withdrawn by unlocking the box, substantially as and for the purpose set forth.

2. The combination of the box B, false bottom D, glass plate F, pins G, and check-plates H, substantially as set forth.

3. In combination with the arm A and box B, the lock-plate C, arranged to operate substantially as and for the purpose set forth.

In testimony whereof, I have signed my name to this specification in the presence of two subscribing witnesses.

SAM'L F. COVINGTON.
